LIQUID FUEL BURNER

Joseph Mohr, Richmond, Va.

Application August 5, 1936, Serial No. 94,458

2 Claims. (Cl. 158—94)

The invention aims to provide an exceptionally simple and inexpensive, yet an efficient and desirable liquid fuel burner which is designed primarily for use in toy motor-boats of the jet type, yet is not restricted to such use.

In carrying out the above end, a further object is to provide a liquid fuel burner of such construction that gravity assists in feeding fuel through a wick-containing tube extending from the fuel reservoir, the discharge of fuel through said tube being throttled to the desired extent by fitting the wick tightly into the tube.

A further object is to provide a fuel reservoir formed from a cylindrical tube preferably closed at one end and having a removable closure at its other end, and to so shape the outer end of said removable closure as to hold the reservoir against lateral tilting when placed upon a support.

Yet another object is to provide a burner particularly adapted for support upon the usual parallel jet tubes which extend rearwardly from the boiler of a toy boat of the jet type.

With the foregoing and minor objects in view, the invention resides in the novel subject matter hereinafter described and claimed, description being accomplished by reference to the accompanying drawing.

Fig. 1 is a side elevation partly broken away and in section showing the burner operatively positioned in a toy boat.

Fig. 2 is a perspective view showing the boiler and jet tubes of the boat, and the burner resting upon said tubes.

Fig. 3 is a central vertical longitudinal sectional view, partly in elevation, through the burner.

Fig. 4 is a transverse sectional view on line 4—4 of Fig. 1.

The fuel reservoir of the burner is formed from a horizontal cylindrical tube 5 having a permanently closed end 6, and an ordinary cork or other plug 7 fitting removably into the other end of said tube. The plug 7 is provided with an enlarged outer end 8 which projects beyond the tube 5, the lower side 9 of said enlarged plug end being flattened or otherwise shaped to prevent the tube from rolling or laterally tilting when placed upon a support.

The plug 7 is formed with a central longitudinal opening 10 through which one end portion of a wick tube 11 is threaded, the screw threads being preferably covered with red lead or other sealing medium before threading the tube through the plug. The outer end portion

of the tube 11 is preferably of substantially U-shape as shown at 12 and terminates in an upwardly directed extremity 13 which is at about the same elevation as the upper side of the tube 5 so that gravity may assist feeding of fuel through the tube 11 but cannot alone accomplish this end. A wick 14 extends through the tube 12 and projects slightly from the terminal 13 thereof, and the natural absorptive qualities of the wick coact with gravity in properly feeding the fuel from the reservoir. To prevent too rapid discharge of fuel, the wick is tightly fitted into the tube, exerting a throttling action.

To permit air to enter the tube 5, as fuel leaves the same, a small air admission opening 15 is formed in the top of said tube 5 a safe distance from the flame end of the burner.

The burner is intended primarily to rest upon the two horizontally spaced and horizontally disposed parallel jet tubes 16 extending rearwardly from the boiler 17 of a toy motor-boat 18, with the burner flame so positioned as to heat the boiler. When used in this way, the tube 5 rests upon and partially between the jet tubes 16 and the lower side 9 of the plug 7 rests upon the upper sides of said tubes 16 to hold the entire burner against any lateral tilting or rolling and to also assist in initially placing the burner in position with the flame directed upwardly against the boiler. With the burner thus supported, it will remain in proper position even though the child playing with the toy may create a rather "rough sea" in which to "navigate" the craft.

The part 19 shown in Fig. 3 is merely a wire 35 connected with the inner end of the wick 14. This wire is used in initially threading the wick through the tube 11 and may be left attached for use when one wick has been consumed and another is to be inserted, preventing loss of the 40 wire.

On account of the extreme simplicity yet efficiency of the specific construction herein disclosed, said construction is preferably followed. However, within the scope of the invention as 45 claimed, variations may be made as to structure and use, and obviously the invention is not restricted to size or proportions. For example, instead of the wick tube 11 being curved as shown, it may be straight with the outer end 50 extending upwardly at a right angle.

I claim:—

1. A liquid fuel burner comprising a horizontal fuel-containing tube having a permanent closure at one end, a plug fitting removably into the 55

other end of said fuel-containing tube and having an enlarged outer end projecting beyond said other end of said fuel-containing tube, a wick tube carried by and projecting outwardly and upwardly from said plug, and a wick in said wick tube, said enlarged outer end of said plug having a flat lower side to prevent the fuel-containing tube from laterally tilting when laid upon a support.

2. A liquid fuel burner comprising a horizontal fuel-containing tube having a permanent closure at one end and a removable closure at its other

end, a wick tube extending outwardly from and carried by said removable closure, said wick tube having an upwardly directed outer end whose upper extremity is at about the same elevation as the top of said fuel-containing tube to permit gravity to assist in feeding fuel through said wick tube, said top of the fuel-containing tube being provided with an air admission opening, and a wick fitting tightly in said wick tube and serving to throttle the passage of fuel there-
5 through.
